UNITED STATES PATENT OFFICE.

JOSEPH M. TOWNSEND, OF WORCESTER, MASSACHUSETTS, ASSIGNOR OF ONE-HALF TO
WALLACE E. FREEMAN, OF WORCESTER, MASSACHUSETTS.

ART OF ENVELOPE MANUFACTURE.

1,426,523.

Specification of Letters Patent. Patented Aug. 22, 1922.

Application filed January 6, 1922. Serial No. 527,399.

To all whom it may concern:

Be it known that I, JOSEPH M. TOWNSEND, a citizen of the United States, residing at Worcester, in the county of Worcester and

5 State of Massachusetts, have invented certain new and useful Improvements in the Art of Envelope Manufacture, of which the following is a full, clear, and exact description.

10 This invention relates to improvements in the art of and machines for envelope manufacture and with regard to certain more specific features thereof to the holding and folding of envelopes and the like, and to

15 devices for accomplishing such results.

The invention has for one of its objects the provision of an inexpensive, reliably operative, and otherwise improved means and method involving a suction device, or the

20 use of vacuum for securing and manipulating a blank of paper or similar material to effectively crease the same along various predetermined lines of fold and, if desired, press upon the folded portions, to cause adherence

25 at their gummed areas.

Other objects will be obvious upon a consideration of the description of one of various possible ways of employing my improved method and the means for carrying

30 the same into effect, which follows herein.

In the accompanying drawings:

Fig. 1 is a view in plan of my improved envelope holding and folding device.

Fig. 2 is a sectional view taken on the line 35 2-2 of Fig. 1, showing the envelope holding means in uppermost position.

Fig. 3 is a similar view, but with the envelope holding means shown in a lower position and the folding fingers moving to complete their respective folds.

A main support, or frame, is indicated at 10. This frame has suitable uprights 11 within which are suitably journaled fingers 12, 13, 14, and 15. While for the purpose 45 of the present case it is unimportant by what means these fingers are actuated, it is of course to be understood that they may be mechanically, electro-magnetically, manually, or otherwise actuated by any suitable 50 means either independently of, or co-operatively associated with, the means for reciprocating the suction block, which will be hereinafter described. Each folding finger ter-

minates at its pivoted end in a roll 16 of substantial diameter and which has a function also to be later described. 55

A suction member or block 20, has a depending stem or shaft 21, which is slidably fitted in the support 10 at its central region. At the end of the stem or shaft there is fitted 60 an eccentric yoke 22 which is operated by an eccentric 23 carried on a shaft 24, which latter may be driven from any suitable source of power. By means of the eccentric 23 the suction member is intermittently lifted to 65 contact with the envelope blank, as indicated at 30 (the blank being fed by suitable mechanism against a stop 31 temporarily positioned, as shown in Fig. 2). The block 20 is provided with a common air chamber 32, 70 which communicates with a plurality of suction apertures indicated at 33. A pipe 34, having a flexible characteristic, communicates with chamber 32 of the suction block, and suitable means (not shown) are provided for exhausting the air from the chambers and conduits of the suction block 75 through said pipe.

The suction apertures are arranged to be substantially co-extensive with, and adjacent to, the proposed lines of fold of the envelope. In the embodiment of the invention shown in the drawings these suction apertures are continuous narrow slots extending almost the entire length and width 85 of the block. Obviously these apertures might be of somewhat different configuration and arrangement without departing from the inventive idea.

Assuming the envelope blank to have attached to the suction block, as shown in Fig. 2, with the block in its uppermost position and firmly holding the envelope blank 90 approximate the predetermined lines of fold, it will be noted that as the suction block is 95 moved downwardly by the eccentric 23, portions of the blank extending beyond the block 20 on all sides are wiped against the rolls 16, which may be considered at that time as substantially fixed parts relatively 100 to the suction block 20. This wiping action gives an initial fold to the envelope flaps, which initial fold is concluded by rapid movement of the folding fingers 12, 13, 14, 105 and 15 in proper sequence, into pressing position on the top of suction member 20. In

this way the envelope blanks are rapidly, accurately, and uniformly folded and creased and, obviously, if the flaps of the blank have been suitably gummed prior to their folding, 5 the pressure exerted by the folding fingers will cause adherence at the points or areas desired.

As many changes could be made in the 10 above construction and as many apparently widely different embodiments of the invention could be made without departing from the scope thereof, it is intended that all matter contained in the foregoing description or 15 shown in the accompanying drawings shall be interpreted as illustrative and not in a limiting sense.

What I claim is:

1. In an envelope folding device, a support, movable members adapted to act upon 20 an envelope blank to fold the same, a movable suction member having suction apertures extending along the lines of proposed fold, said block being movable to a position to attach the blank by suction, then movable 25 with the attached blank, to cause a wiping

action on portions of the blank to initiate the folding operation.

2. In an envelope folding device, a substantially flat pad having a plurality of slot like suction apertures substantially coextensive with and arranged adjacent folding fingers, a folding finger for each line of fold, means for moving the suction block into position to attach an unfolded blank and for moving said block in the opposite direction 30 to initiate the folds by a wiping action of extending portions of the blank upon other parts of the device.

3. The method of folding envelopes which consists in depositing a blank upon a holding 40 and folding device, creating a vacuum below said blank substantially along predetermined lines of fold, moving the blank, while under the influence of the vacuum, to cause portions of the blank extending beyond said lines of 45 fold to be wiped against relatively stationary parts and partially folded, and acting upon said partially folded portions to complete the folds.

JOSEPH M. TOWNSEND.
